GRINDING MACHINE

Oiva E. Hill, Worcester, Mass., assignor to Norton Company, Worcester, Mass., a corporation of Massachusetts

Application December 5, 1956, Serial No. 626,484

8 Claims. (Cl. 51—165)

The invention relates to grinding machines and more particularly to a wheel feeding and wheel truing apparatus.

One object of the invention is to provide a simple and thoroughly practical grinding machine feeding and truing apparatus. Another object is to provide a truing apparatus which may be operated either intermittently or continuously. Another object is to provide a truing tool feeding mechanism by which the truing tool may be fed at each end of a reciprocatory stroke either at a fine feed for continuous truing or at a coarser feed for intermittent truing.

Another object of the invention is to provide a manually operable clutch mechanism whereby either a fine feed for continuous truing, or a coarser feed for an intermittent feed may be obtained at each end of the traversing stroke of the truing tool.

A further object of the invention is to provide a grinding wheel feed compensating mechanism which is arranged to impart a fine compensating adjustment after each complete reciprocation of the truing tool, or a coarser compensating adjustment after each reciprocation of the truing tool when set up for intermittent truing to compensate for wheel wear and truing. Other objects will be in part obvious or in part pointed out hereinafter.

In the accompanying drawings, in which is shown one of various possible embodiments of the mechanical features of this invention:

Fig. 1 is a fragmentary sectional view through a grinding machine showing the wheel feeding mechanism;

Fig. 2 is a vertical sectional view, on an enlarged scale, taken approximately on the line 2—2 of Fig. 1, showing the wheel feed compensating mechanism;

Fig. 3 is a vertical view, taken approximately on the line 3—3 of Fig. 2, through the feed compensating mechanism;

Fig. 4 is a vertical sectional view, taken approximately on the line 4—4 of Fig. 2, through the feed compensating mechanism;

Fig. 5 is a vertical sectional view through the grinding wheel truing apparatus;

Fig. 6 is a fragmentary plan view of the truing apparatus as shown in Fig. 5 having parts broken away and shown in sections; and

Fig. 7 is a combined hydraulic and electric diagram of the actuating mechanisms and the controls therefor.

A cylindrical grinding machine has been illustrated in the drawings comprising a base 10 which supports a transversely movable wheel slide 11 on the usual ways formed on the upper surface of the base 10. The wheel slide 11 supports a rotatable wheel spindle 12 in the usual spindle bearings (not shown). A grinding wheel 13 is mounted on one end of the spindle 12.

A driving mechanism is provided for imparting a rotary motion to the wheel spindle 12 and the grinding wheel 13 comprises an electric motor 14 mounted on the upper surface of the wheel slide 11. The motor is provided with a motor shaft 15 having a multiple V-groove pulley 16

2

which is connected by multiple V-belts 17 with a multiple V-groove pulley 18 mounted on the other end of the wheel spindle 12.

A wheel feeding mechanism is provided comprising a rotatable feed screw 20, the right hand end of which is journaled in anti-friction bearings 21 carried by a slidably mounted sleeve 22 which is supported in a cylindrical aperture 23 formed in the base 10. The left hand end of the feed screw 20 is slidably keyed within a rotatable sleeve 24 which is journaled in an anti-friction bearing 25 supported by the base 10. The wheel slide 11 is provided with a depending half-nut 26 which meshes with or engages the feed screw 20.

A manually operable feeding mechanism is provided for the feed screw 20 comprising a manually operable feed wheel 27 which is rotatably supported on a shaft 28. The feed wheel 27 is connected by a well known micrometer feed adjusting mechanism 29 with a pinion 30 which meshes with a gear 31 rotatably supported on the shaft 28. A gear 32 is fixedly mounted to the gear 31 and meshes with a gear 33 which is keyed onto the left hand end of a rotatable shaft 34. The left hand end of the shaft 34 is journaled in an anti-friction bearing 35. The right hand end of the shaft 34 is rotatably supported within a hollow shaft 36 which is slidably keyed within the sleeve 24. A wheel feed compensating mechanism, to be hereinafter described is connected between the shaft 34 and the hollow shaft 36 to impart a rotary motion to the feed screw 20 when the feed wheel 27 is rotated.

A hydraulically operated mechanism is provided for imparting a rotary motion to the feed screw 20. This mechanism has not been illustrated in detail in the present application since it is substantially identical with that shown in the prior U.S. Patent No. 2,572,529 to H. A. Silven dated October 23, 1951. This mechanism comprises a cylinder 40 which contains a slidably mounted piston 41. The upper surface of the piston 41 is provided with rack teeth 42 which mesh with a gear 43 which is rotatably journaled in spaced anti-friction bearings 44 and 45. A shaft 46 is rotatably journaled within the gear 43 and is provided with a gear 47 fixedly mounted on the right hand end thereof (Fig. 1). A clutch mechanism is provided for connecting the gear 43 to the shaft 46. This clutch mechanism comprises an internal gear-shaped clutch element 48 which as shown in Fig. 1 meshes with an external gear-shaped clutch element 49. An actuating knob 50 is mounted on the left hand end of the shaft 46. When it is desired to declutch the shaft 46 and the gear 47 from the gear 43, the knob 50 is moved toward the right 50 to shift the shaft 46 toward the right so as to slide the internal gear-shaped clutch element 48 out of mesh with the gear-shaped clutch element 49.

The gear 47 meshes with a gear 55 which is keyed to the shaft 34. A gear 56 is fixedly mounted relative to the gear 55 and meshes with a pinion 57 formed on the left hand end of a shaft 58. The shaft 58 is supported within a casing 59 which supports the feed compensating mechanism. The casing 59 supports a shaft 60 which is provided with a gear 61 on its right hand end. The gear 61 meshes with a gear 62 which is fixedly mounted on the hollow shaft 36. The shafts 58 and 60 are normally held against rotation relative to the casing 59 in a manner to be hereinafter described. It will be readily apparent that a rotary motion imparted to the gear 55, either by 65 the manually operable feed wheel 27 or the piston 42 will be imparted through the gear 55 to rotate the gear 56. Due to the fact that the shafts 59 and 60 are normally held against rotary motion, a rotary motion of the gear 56 will be transmitted through the pinion 57 to rotate the casing 59. Rotary motion of the casing 59 serves to cause the gear 61 to impart a rotary motion to the gear 62 thereby imparting a rotary motion to the

feed screw 20. The direction of rotation of the feed wheel 27 or the direction of the movement of the piston 41 serves to determine whether a forward or rearward movement of the wheel slide 11 is obtained.

A wheel feed compensating mechanism is provided which operates and in timed relation with a grinding wheel truing apparatus to be hereinafter described. The truing apparatus is arranged so that either an intermittent or a continuous truing operation may be obtained. A duplex wheel feed compensating mechanism is provided so that wheel compensation may be made either during an intermittent truing operation of the wheel or during a continuous truing operation on the grinding wheel.

The compensation of the wheel feed mechanism for continuous truing of the grinding wheel will now be described. A hydraulically operated feed compensating unit 64 is supported on the shaft 34 and is provided with a cylinder 65 (Fig. 7) which contains a slidably mounted piston 66. The piston 66 carries a spring pressed pawl 67 which is arranged to engage the teeth of a ratchet wheel 68. The ratchet wheel 68 is mounted on the left hand end of a rotatable shaft 69 which also supports a worm 70 meshing with a worm gear 71 (Figs. 2 and 3) keyed onto the shaft 58. A compression spring 72 (Figs. 3 and 7) serves normally to hold the piston 66 in a downward position. When it is desired to cause a compensating adjustment of the wheel feed during continuous truing, fluid under pressure is passed from valve chamber 109 and through the pipes 76 and 78 into a cylinder chamber 73 to cause an upward movement of the piston 66. During the upward movement of the piston 66 the pawl 67 rides idly over the teeth of the ratchet wheel 68 (Figs. 3 and 7). The upward movement of the piston 66 continues until a piston rod 74 attached to the upper end of the piston 66 engages an adjustable stop screw 75. The piston 66 remains in this position until the piston 128 and truing tool 138 start traversing toward the left. When fluid under pressure is allowed to exhaust from the cylinder chamber 73, the released compression of the spring 72 causes a downward movement of the piston 66 during which movement the pawl 67 turns the ratchet wheel 68 to impart a compensating adjustment to the feed screw 20 as the truing tool 138 starts its traversing stroke toward the left. The operative connections between the continuous compensating adjusting mechanism and the feed screw 20 are such that for each tooth on the ratchet wheel, a compensating adjustment will be imparted to the feed screw to advance the wheel slide 11 .00001 of an inch. The number of teeth the ratchet wheel 68 is indexed during each compensating adjustment may be determined by the upward movement of the piston 66 as governed by the stop screw 75.

A compensating adjustment by the mechanism above described during a continuous grinding wheel truing operation is obtained in the following manner. Rotary motion of the worm gear 71 imparts a rotary motion to the pinion 57 to cause the pinion 57 to roll upon the gear 56 thereby imparting a slight rotary motion to the casing 59 (Fig. 1). The rotary motion of the casing 59 is transmitted through the now stationary gear 61 to impart a rotary motion to the gear 62 and thereby to impart a compensating adjustment to the feed screw 20. When fluid under pressure is passed through a pipe 76, through a control valve 77 and through a pipe 78 into the cylinder chamber 73, the continuous truing compensator is actuated, as above described.

The wheel feeding compensating mechanism for compensating during an intermittent grinding wheel truing operation will now be described. The feed compensating unit 64 is provided with a cylinder 85 which contains a slidably mounted piston 86. The piston 86 carries a spring pressed pawl 87 which is arranged to engage the teeth of a ratchet wheel 88. The ratchet wheel 88 is

mounted on the right hand end of a rotatable shaft 89 (Fig. 2) which also supports a worm 90 meshing with a worm gear 91 keyed onto the shaft 60 (Fig. 2). A compression spring 92 (Figs. 4 and 7) serves normally to hold the piston 86 in an upward position. When it is desired to cause a compensating adjustment of the wheel feeding mechanism during an intermittent grinding wheel truing operation, fluid under pressure is passed to a cylinder chamber 93 to cause a downward movement of the piston 86. During the downward movement of the piston 86 the pawl 87 engaging the teeth of the ratchet wheel 88 imparts a counter-clockwise rotary movement to the ratchet wheel 88 and the shaft 89. The worm 90 and the gearing associated with the compensating mechanism are such that for each tooth on the ratchet wheel 85, a feed compensating adjustment of .0005 of an inch adjustment is made. The downward movement of the piston 86 continues until a rod 94 attached to the lower end of the piston 86 engages an adjustable stop screw 95. When fluid is allowed to exhaust from the cylinder chamber 93 the released compression of the spring 92 causes an upward movement of the piston 86 during which movement the pawl 87 rides idly over the teeth of the ratchet wheel 88. The number of teeth of the ratchet wheel 88 which are picked up at each actuation of the compensating mechanism is determined by the adjustment of the stop screw 95.

A compensating adjustment by the mechanism above described during an intermittent grinding wheel truing operation is obtained in the following manner. Rotary motion of the worm gear 91 serves to impart a rotary motion to the shaft 60 and the gear 61 to impart a corresponding rotary motion to the gear 62 and the feed screw 20. During this compensation, no rotary motion is imparted to the casing 59 relative to the shaft 34.

When fluid under pressure is passed through a pipe 96, through a control valve 97 and through a pipe 98 into the cylinder chamber 93, a compensating feed adjustment is made when the truing tool 138 starts traversing toward the left across the operative face of the grinding wheel during an intermittent truing operation.

Only one of the feed compensators is operative at a given time. If the truing apparatus to be hereinafter described is set for automatic continuous truing of the grinding wheel the valve 97 is manually closed to render cylinder 85 and the associated parts of the intermittent compensating mechanism inoperative. Similarly if the truing apparatus is set for an intermittent truing operation, the valve 77 is closed and the valve 97 opened thereby rendering the cylinder 65 and the associated parts of the continuous compensating mechanism are rendered inoperative. The feed compensation takes place when the truing tool 138 starts traversing toward the left regardless of whether the truing apparatus is set for intermittent or continuous truing.

The grinding wheel feed mechanism during normal operation of the grinding machine regardless of whether it is manually or hydraulically operated is unwound and wound in a manner substantially the same as that disclosed in the above mentioned U.S. Patent No. 2,572,529, that is, after a grinding operation has been completed and before the grinding starts on the next work piece. This unwinding and winding of the wheel feeding mechanism, not only takes up any backlash in the feed mechanism parts but also finds the compensation increment or increments in a manner similar to that to be hereinafter described in connection with the grinding wheel truing apparatus.

A fluid pressure system is provided for supplying fluid under pressure to the various mechanisms of the machine. This system may comprise a motor driven fluid pump 100 which may be started by closing a manually operable switch 99. The pump 100 draws fluid through a pipe 101 from a reservoir 102 and forces fluid under pressure through a pipe 103. A relief valve 104 is connected in

the pipe line 103 to facilitate by passing excess fluid under pressure directly from the pipe 103 into the reservoir 102 so as to maintain a substantially uniform operating pressure within the fluid system.

A control valve 105 is provided comprising a valve stem 106 having a plurality of spaced valve pistons forming a plurality of spaced valve chambers 107, 108, and 109. The slidably mounted valve member is provided with a central passage 110 which interconnects the valve chamber 107 with the valve chamber 109. A compression spring 111 serves normally to hold the valve stem 106 in a left hand end position, as shown in Fig. 7. A solenoid S1 is provided which when energized serves to shift the valve stem into a rearward end position. A pipe 112 exhausts fluid from the control valve 105 through a throttle valve 113 and through a pipe 114 into the reservoir 102. The control valve 105 serves in a manner to be hereinafter described to control the admission to an exhaust of fluid from the feed compensating mechanisms above described and also to a grinding wheel truing mechanism to be hereinafter described.

The grinding wheel 13 is partially surrounded by a wheel guard 120 which is fastened to or fixedly mounted on the wheel slide 11. The wheel guard 120 is provided with an upwardly extending housing 121 which serves as a support for a grinding wheel truing apparatus 122. The truing apparatus 122 is similar to that disclosed in my prior U.S. Patent No. 2,647,504 dated August 4, 1953. The truing apparatus is provided with a longitudinally movable slide 123 (Fig. 5) which is supported by anti-friction slide-ways 124 and 125 carried by a truing apparatus base 126. A hydraulically operated mechanism is provided for traversing the slide 123 longitudinally. This mechanism comprises a cylinder 127 which contains a slidably mounted piston 128 (Fig. 7). The piston 128 is connected to the right hand end of a piston rod 129, the left hand end of which is fixedly mounted to the slide 123. It will be readily apparent from the foregoing disclosure that when fluid under pressure is passed through the pipe 76 into a cylinder chamber 130 at the left hand end of the cylinder 127, the piston 128 together with the slide 123 will be traversed toward the right. During this movement fluid within a cylinder chamber 131 exhausts through the pipe 96. Similarly when fluid under pressure is passed through the pipe 96, the piston 128 together with the slide 123 will be moved or traversed toward the left (Fig. 7).

The longitudinally movable slide 123 supports a vertically arranged sleeve 135. A vertically arranged truing tool holder shaft 136 is supported within the sleeve 135. A truing tool holder 137 having a diamond or truing tool 138 is mounted at the lower end of the shaft 136. The sleeve 135 is arranged to slide vertically within the slide 123. A follower 139 is fastened to the sleeve 135 and rides upon a forming bar 140 which is fixedly mounted on the truing apparatus base 126. In the present case the forming bar 140 is provided with a plane face so that the truing tool will be moved in a straight line path when the longitudinally movable slide 123 is traversed.

A suitable feeding mechanism is provided for adjusting the truing tool 138 vertically relative to the sleeve 135 and the slide 123. This mechanism comprises a feed screw 141 formed on the upper end of the truing tool holder shaft 136. A rotatable feed nut 142 meshes with the feed screw 140. A gear 143 is keyed to the feed nut 142 and meshes with a small gear 144 which is keyed on a rotatable shaft 145. The upper end of the shaft 145 is provided with a manually operable feed wheel 146 by means of which the nut 142 may be rotated in either direction vertically to adjust the position of the truing tool 138.

The grinding wheel truing apparatus is preferably arranged so that either a manually controlled intermittent or a continuous grinding wheel truing cycle may be obtained. A truing tool feeding mechanism is provided

which is actuated at the ends of the reciprocating stroke of the truing tool 138. The feed nut 142 is first unwound or backed-off at which time the feed nut 142 is then given a predetermined incremental rotary motion to feed the truing tool downwardly by a predetermined increment after which the feed nut is wound or advanced to a predetermined stopped position before the truing tool 138 starts its traverse across the periphery face of the grinding wheel 13. The winding and unwinding of the feed nut before and after the incremental feeding movement serves to take up backlash in the feed mechanism parts.

An oscillatable plate 150 (Figs. 5 and 6) is rotatably supported on the hub 151 formed integral with the gear 143. The plate 150 serves as a support for the rotatable shaft 145 and also for the truing tool feeding mechanism to be hereinafter described. The plate 150 is normally held in the position shown in Figure 6 with the stop surface 152 in engagement with an adjustable stop screw 153 by means of a compression spring 154. The spring 154 is interposed between a bracket 155 which is fixed relative to the truing apparatus slide 123 and a lug 156 depending from the plate 150.

When the slide 123 moves longitudinally toward the right (Fig. 6), a rearwardly projecting arm 157 formed integral with the plate 150 engages a stud 158 carried by an adjustable dog 159 which serves to rock the plate 150 in a counter-clockwise direction. This movement of the plate 150 serves to move the, now held stationary, gear 144 to impart a counter-clockwise rotary motion to the gear 143 (Fig. 6) and the truing tool feed nut 142 to impart counterclockwise unwind movement to the feed nut 142 in a manner to be hereinafter described. As soon as the slide 123 starts moving toward the left, the released compression of the spring 154 rocks the plate 150 in a clockwise direction until the stop surface 152 engages the stop screw 153 thereby imparting a rotary motion to the feed nut 142 to position the truing tool 138 for a traversing movement toward the left across the operative face of the grinding wheel 13.

Similarly, as the slide 123 approaches the end of its traverse toward the left, a cam 162 on the plate 150 engages a stud 160 on an adjustable dog 161. Continued movement of the slide 123 toward the left serves to rock the plate 150 in a counter-clockwise direction to unwind the feed nut 142 at which time a rotary feeding increment is imparted to the nut 142. The nut 142 remains in this position until the slide 123 starts a traversing movement toward the right at which time the released compression of the spring 154 rocks the plate 150 in a clockwise direction until the stop surface 152 engages the stop screw 153 thereby imparting a wind motion to the feed nut 142 so as to position the truing tool 138 for a pass toward the right across the operative face of the grinding wheel 13. It will be readily apparent from the foregoing that each time the slide 123 approaches either end of its longitudinal traversing movement, the feed nut 142 is backed-off or unwound, a feeding increment is imparted to the feed nut 142 and as soon as the slide starts moving in the opposite direction, a rotary motion wind is imparted to the feed nut 142 thereby taking up backlash in the feed mechanism parts and at the same time imparting a feeding increment to the truing tool 138.

A truing tool feed unit 165 (Figs. 5, 6 and 7) is provided which is fixedly mounted on the underside of the plate 150. The unit 165 together with the plate 150 serves rotatably to support the shaft 145. A ratchet wheel 166 and a worm gear 167 are rotatably supported on the shaft 145 and arranged so that one or the other may be clutched to the shaft 145, as desired. The shaft 145 is arranged for an axial movement relative to the unit 165 so that a drive pin 168 (Fig. 5) fixedly mounted on the shaft 145 may be engaged with a notch in the

hub of the ratchet wheel 166 (Figs. 5 and 7) to lock the ratchet wheel to the shaft 145. Or the shaft 145 may be moved upwardly so that the drive pin 168 engages a notch formed in the downwardly projecting hub of the worm gear 167. A spring-pressed detent 169 (Fig. 5) is arranged to engage one of a plurality of grooves formed in the periphery of the shaft 145 so as to facilitate holding the shaft to engage either the ratchet wheel 166 or the worm gear 167 relative thereto. If the shaft 145 is moved vertically so that the detent 169 engages a central groove, the drive pin 168 is in a neutral position in which position both the ratchet wheel 166 and the worm gear 167 are declutched from the shaft 145. If a very fine feeding increment is desired, the shaft 145 is moved upwardly so that the detent 169 engages the lower groove of the shaft 145 to position the drive pin 168 in an uppermost position so as to lock the worm gear 167 relative to the shaft 145.

A fluid pressure operative mechanism is provided for actuating the ratchet wheel 166 which is arranged so that a feeding down movement of the truing tool 138 may be obtained automatically at the ends of the traversing stroke of the truing tool. This mechanism comprises a cylinder 175 (Fig. 7) which contains a slidably mounted piston 176. The piston 176 is provided with a spring actuated pawl 177 which is arranged to engage the teeth of the ratchet wheel 166. A compression spring 178 serves normally to hold the piston 176 in an uppermost position. The piston 176 is provided with a downwardly extending projection 179 which is arranged to engage a stop screw 180 to determine the stroke of the piston 176 and thereby to determine the number of teeth of the ratchet wheel 166 which are picked at each reciprocation of the piston 176. When fluid under pressure is passed through a pipe 181 into a cylinder chamber 182, the piston 176 is moved downwardly so that the pawl 177 rides idly over the teeth of the ratchet wheel 166. When fluid is exhausted from the pipe 181 from the cylinder chamber 182, the released compression of the spring 178 causes an upward movement of the piston 176 during which movement the pawl 177 engages the teeth of the ratchet wheel 166 and turns it one or more teeth in a clockwise direction (Fig. 7). The number of teeth picked is determined by the setting of the stop screw 180. The mechanism above described serves to initiate a down feeding movement of the truing tool 138 as it starts a traversing movement toward the right.

A similar mechanism is provided for imparting a downward feeding movement to the truing tool 138 as it starts a traversing movement toward the left. This mechanism comprises a cylinder 185 which contains a slidably mounted piston 186. The piston 186 is provided with a spring pressed pawl 187 which is arranged to engage the teeth of the ratchet wheel 166. A compression spring 188 serves normally to hold the piston 186 in an uppermost position. The piston 186 is provided with a downwardly extending projection 189 which is arranged to engage an adjustable stop screw 190. The setting of the adjusting screw 190 serves to determine the number of teeth of the ratchet wheel 166 picked by the pawl 187 during each actuation of the piston 186. When fluid under pressure is passed through the pipe 191 into a cylinder chamber 192, the piston 186 is moved downwardly during which movement the pawl 187 engages the teeth of the ratchet wheel 166 and imparts a clockwise rotary motion to the ratchet wheel 166.

A shuttle type valve 195 is provided which is actuated by and in timed relation with the movement of the piston 128. The valve 195 comprises a slidably mounted valve member having a plurality of valve pistons formed integrally therewith to form spaced valve chambers 197 and 198. When fluid under pressure is passed through the pipe 76 into the cylinder chamber 130 to start the piston 128 together with the truing tool 138 moving

toward the right, fluid under pressure passes through a passage 199 into the valve chamber 197 and through the pipe 181 into the cylinder chamber 182 to impart an idle movement to the pawl 177. At the same time fluid under pressure passing through the passage 199 enters an end chamber 200 and moves the slidably mounted valve member toward the right. When the valve member moves a sufficient distance toward the right to first cover and then uncover the port to the end of the pipe 201, fluid under pressure is cut off from the valve chamber 197 and the valve chamber 197 is opened to exhaust fluid from the cylinder chamber 182, through the pipe 181, through the valve chamber 197 and through a pipe 201 into the reservoir 102. The movement of the slidably mounted valve member 196 requires less fluid under pressure than that required to move the piston 128, consequently the valve member 196 moves rapidly toward the right so that a momentary shot of fluid causes a downward movement of the piston 176 to cause the pawl 177 to ride idly over the teeth of the ratchet wheel 166 after which the released compression of the spring 178 causes an upward movement of the piston 176 and the pawl 177 to impart an indexing movement to the ratchet wheel 166 thereby imparting a rotary motion to the shaft 145 (Fig. 5) to rotate the small gear 144, the large gear 143 and the feed nut 142 to impart a downward feeding movement to the truing tool 138.

During the movement of the valve member 196 toward the right fluid within an end chamber 202 exhausts through a passage 203 into the cylinder chamber 131 and through the pipe 96.

When the slide 123 together with the piston 128 and the truing tool 138 are at the right hand end of the traversing movement, when fluid under pressure is reversed and passed through the pipe 96 into the cylinder chamber 131, fluid passes through the passage 203, through the valve chamber 198, through the pipe 191 into the cylinder chamber 192 to cause downward feeding movement of the pawl 187 which imparts a rotary motion to the ratchet wheel 166 and through the mechanism previously described to impart a down feeding movement to the truing tool 138. As previously described the passage of fluid under pressure into the cylinder chamber 131 passes through the passage 203 into the valve chamber 198 and at the same time passes into the valve chamber 202 rapidly to move the valve member 196 toward the left. During movement of the valve member 196 toward the left a momentary shot of fluid under pressure passes through the pipe 191 to cause the downward movement of the piston 186 to index the ratchet wheel 166 after which the released compression of the spring 188 causes an upward movement of the piston 186 so that fluid within the cylinder chamber 192 exhausts through the pipe 191, through the valve chamber 198 and through the pipe 201 into the reservoir 102. This feeding mechanism above described serves to impart a controlled down feeding movement of the truing tool at each end of the traversing stroke of the truing tool during an intermittent truing operation which may be manually initiated in a manner to be hereinafter described.

The grinding wheel truing apparatus is arranged so that a continuous truing of the grinding wheel may be obtained when desired. In this case a continuous reciprocation of the truing tool is provided with a fine down feeding movement of the truing tool at the end of each stroke of the truing tool slide. The worm gear 167 meshes with a worm 210 which is mounted on a rotatable shaft 211 (Fig. 6). A pair of spaced ratchet wheels 212 and 213 are mounted adjacent to opposite ends of the shaft 211. In actual construction as shown in Fig. 5 the ratchet wheels 212 and 213 together with the shaft 211 are arranged at right angles to the ratchet wheel 166 and the shaft 145. As shown diagrammatically in Fig. 7 the shaft 211 together with the ratchet wheels 212 and

213 are shown in the same plane with the ratchet wheel 166.

A spring actuated pawl 214 is carried by the piston 176 and a spring pressed pawl 215 is mounted on the piston 186. When it is desired to obtain a fine feed during continuous truing operation, the knob 146 together with the shaft 145 are moved upwardly so that the detent 169 engages the lower groove on the shaft 145 and so that the driving pin 168 engages the notch in the hub of the worm gear 167. In this position of the parts when fluid under pressure is admitted to the cylinder chamber 130 to cause the piston 128 together with the slide 123 to move toward the right, fluid under pressure is passed through the passage 199 and momentarily through the valve chamber 197 through the pipe 181 into the cylinder chamber 182 to cause a downward movement of the piston 176 and the pawl 214. The pawl 214 engaging the ratchet wheel 212 imparts a rotary motion to the shaft 211 and through the worm 210 and worm gear 167 to impart a downward feeding movement to the truing tool 138. The valve member 196 moves rapidly toward the right so that fluid from the cylinder chamber 182 may exhaust through the valve chamber 197 and through the pipe 201 into the reservoir 102 under the influence of the released compression of the spring 178 thereby returning the piston 176 together with the pawl 214 to their initial positions as illustrated in Fig. 7.

Similarly when fluid under pressure is admitted to the cylinder chamber 131 to start movement of the piston 128 together with the slide 123 toward the left, fluid passes through the passage 203 into the valve chamber 198 and through the pipe 191 into the cylinder chamber 192 to cause a downward movement of the piston 186 together with the pawl 215 thereby imparting a rotary motion to the ratchet wheel 213 which causes a fine downward feeding of the truing tool 138. The valve member 196 moves rapidly toward the left so that pressure passes only momentarily through the valve chamber 198 and the pipe 191. When the valve member 196 reaches the left hand end position, as shown in Fig. 7, the released compression of the spring 188 causes an upward movement of the pawl 215 and the piston 186 so that fluid within the cylinder chamber 192 exhausts through the pipe 191 through the valve chamber 198 and through the exhaust pipe 201 into the reservoir 102 thereby returning the pawl 215 and piston 186 to an uppermost position.

As shown diagrammatically in Fig. 7, the ratchet wheels 212 and 213 and associated parts are illustrated at right angles to their normal position so as to clarify the operation of the mechanism. The ratchet wheel 212 is shown as swung 90° to the left whereas the ratchet wheel 213 is shown as swung at 90° toward the right so that actuation of either or both of the ratchet wheels imparts a rotary motion to the shaft 211 in the same direction.

A manually operable knob 220 is mounted on the shaft 211 to facilitate manual rotation of the shaft 211 to facilitate setting up the truing apparatus and positioning of the truing tool 138.

The operation of the improved grinding wheel truing apparatus will be readily apparent from the foregoing disclosure. With the parts positioned as shown in Fig. 5, the apparatus is set for an intermittent truing operation since the driving pin 168 is in engagement with the notch in the hub of ratchet wheel 166. The switch 99 is manually closed to start the driving motor for the fluid pump 100. A manually operable switch 216 is closed to start the wheel driving motor 14. When it is desired to start an intermittent truing cycle, the start switch PB1 is momentarily closed to energize the relay switch CR1. The energizing of relay switch CR1 sets up a holding circuit through the contacts 217 and through a normally closed limit switch LS1. At the same time the contacts 218 of the relay switch CR1 close

to energize the solenoid S1 to shift the control valve 105 toward the right so that fluid under pressure from the pipe 103 passes through the valve chamber 108, through the pipe 76 into the cylinder chamber 130 to start the piston 128 and the slide 123 moving toward the right (Fig. 7). Fluid under pressure passes from the cylinder 130 through the passage 199, through the pipe 181 into the cylinder chamber 182 to cause a downward movement of the piston 176 thereby causing the pawl 177 to ride idly over the teeth of the ratchet wheel 166. The valve member 196 moves rapidly toward the right so that fluid under pressure passes only momentarily through the pipe 181. As soon as the valve member 196 reaches a right hand end position, the released compression of the spring 178 causes an upward movement of the piston 176 and the pawl 177 thereby imparting a rotary motion to the ratchet wheel 166 which imparts a predetermined down feeding movement to the truing tool 138 in a manner previously described. This feeding movement takes place before the truing tool 138 moves into engagement with the peripheral face of the grinding wheel 13. When the slide 123 together with the truing tool 138 reach the right hand end of their stroke, the slide 123 engages the actuating plunger of the limit switch LS1 and opens the contacts thereof thereby breaking the holding circuit to deenergize the relay switch CR1. The deenergizing relay switch CR1 serves to deenergize the solenoid S1 so that the released compression of the spring 111 shifts the valve stem 106 toward the left into the position illustrated in Fig. 7. In this position of the valve 105 fluid under pressure entering the valve chamber 108 passes through the pipe 96 into the cylinder chamber 131 to start the piston 128 together with the slide 123 moving toward the left. At the same time fluid under pressure in the cylinder chamber 131 passes through the passage 203, through the valve chamber 198, through the pipe 191 into the cylinder chamber 192 to cause a downward movement of the piston 186 thereby moving the pawl 187 downwardly to impart a rotary motion to the ratchet wheel 166 which is transmitted to cause a predetermined down feeding movement of the truing tool 138 before the truing tool moves into engagement with the operative face of the grinding wheel 13. Fluid under pressure is passed only momentarily through the pipe 191. The valve member 196 moves rapidly toward the left so that the released compression of the spring 188 exhausts fluid from the cylinder chamber 192, through the pipe 191, through the valve chamber 198 and through the pipe 201 into the reservoir 102. By manipulation of the stop screws 180 and 190, the extent of down feed of the truing tool 138 at each end of the traversing stroke may be varied as desired.

When the truing apparatus is set for an intermittent truing operation, the valve 97 is opened and the valve 77 is closed so as to render the intermittent compensator piston 66 inoperative and to render the continuous truing compensator piston 86 operative: so that when the truing tool 138 starts traversing toward the left, fluid under pressure is passed through the pipe 96 it passes through the pipe 98 into the cylinder chamber 93 to cause a downward movement of the piston 86. The downward movement of the piston 86 causes a downward movement of the pawl 87 to impart a rotary motion to the ratchet wheel 88 to automatically impart a compensating adjustment to the wheel feed mechanism as previously described. The compensating mechanism is arranged so that each tooth on the ratchet wheel 88 which is picked by the downward movement of the pawl 87 gives a .0005 of an inch compensating adjustment to the feed screw 20. A push button stop switch PB2 is provided to facilitate stopping the truing cycle at any time desired. When the apparatus is set for intermittent truing operation the diamond or truing tool 138 makes

one complete reciprocation across the operative face of the grinding wheel and then stops in the position shown in Figure 7.

When it is desired to provide an automatic continuous truing of the grinding wheel during a grinding operation, a manually operable switch SW1 may be closed. The switch SW1 is connected in series with a normally open limit switch LS2. The closing of the switch SW1 serves to energize the relay switch CR1 to start a traversing movement of a truing tool 138 toward the right. When the apparatus is set for continuous truing, the valve 77 is opened and the valve 97 closed thereby rendering the feed compensator 85 operative during a continuous truing operation. During a continuous truing operation the piston 128 together with the slide 123 reciprocates continuously so as to continuously reciprocate the truing tool 138 across the operative face of the grinding wheel 13. A fine down feeding movement of the diamond or truing tool 138 is obtained at each end of the truing tool stroke. During this operation, the knob 146 is moved upwardly so that the drive pin 168 engages the notch in the worm gear 167. When fluid under pressure is passed through the pipe 181 at the start of a traversing movement of the truing tool 138 toward the right, the piston 176 together with the pawl 214 moves downwardly so that the pawl 214 imparts a rotary motion to the ratchet wheel 212 which is transmitted through the worm 210 and the worm gear 167 to impart a fine down feeding movement to the truing tool 138 before the truing tool moves into engagement with the operative face of the grinding wheel 13.

When the slide 123 approaches the end of its stroke toward the right, the limit switch LS1 is opened to deenergize the relay switch CR1 thereby deenergizing the solenoid S1 so that the valve 105 shifts into the position illustrated in Fig. 7. In this position, fluid under pressure passes through the pipe 96 into the cylinder chamber 131 to start the movement of the piston 128 and the slide 123 toward the left. At this time fluid under pressure passes momentarily through the pipe 191 into the cylinder chamber 192 to cause a downward movement of the piston 186 so that the pawl 215 imparts an indexing movement to the ratchet wheel 213. Rotary motion of the ratchet wheel 213 is imparted through the worm 210 and the worm gear 167 to impart a fine down feeding movement to the truing tool 138 before it moves into engagement with the operative face of the grinding wheel on its stroke toward the left. The feed compensating mechanism is adjusted so that one compensation is imparted to the feed screw 20 during each complete reciprocation of the truing tool when the truing tool 138 starts traversing toward the left.

As the slide 123 approaches the left hand end of its stroke during a continuous truing cycle, it closes the normally open limit switch LS2 to again energize the relay switch CR1 to start the next reciprocation of the truing tool 138. It will be readily apparent from the foregoing disclosure that each time the truing tool starts a traversing movement, a down feeding movement is imparted to the truing tool 138 when the apparatus is set up for either intermittent or continuous truing. As previously stated only one compensation is made to the feeding mechanism for each complete reciprocation of the truing tool when the truing apparatus is set up for either intermittent or continuous operation.

When it is desired to stop a continuous truing cycle, the switch SW1 is opened thereby rendering the limit switch LS1 inoperative so that the slide 123 and truing tool 138 will stop after one complete reciprocation.

It will thus be seen that there has been provided by this invention a grinding wheel truing apparatus in which the various objects hereinabove set forth together with many thoroughly practical advantages are successfully achieved. As many possible embodiments may be made of the above invention and as many changes might be

made in the embodiment above set forth, it is to be understood that all matter hereinbefore set forth or shown in the accompanying drawings is to be interpreted as illustrative and not in a limiting sense.

5 I claim:

1. In a grinding machine having a transversely movable wheel slide, a rotatable grinding wheel thereon, a feeding mechanism to impart a feeding movement to said slide in either direction, a grinding wheel truing apparatus including a longitudinally traversable truing tool, means to reciprocate said truing tool either through one complete reciprocation for an intermittent truing cycle or to reciprocate said truing tool continuously for a continuous truing cycle, a truing tool feed mechanism to feed said truing tool transversely, means actuated by and in timed relation with the longitudinal movement of the truing tool to actuate said truing tool feeding mechanism at each end of the truing tool traverse either at a fine feed for a continuous truing cycle or at a coarser feed for an intermittent truing cycle, and a wheel feed compensator mechanism actuated by and in timed relation with the longitudinal traversing movement of the truing tool automatically to impart a compensating adjustment to the wheel feeding mechanism each time the truing tool reciprocates, said feed compensation being arranged so as to impart either a fine adjustment during a continuous truing cycle or a coarser adjustment during an intermittent truing cycle.

2. In a grinding machine having a transversely movable wheel slide, a rotatable grinding wheel thereon, means including a nut and screw feed mechanism operatively connected to feed said slide in either direction, a grinding wheel truing device including a longitudinally traversable truing tool slide, a transversely movable truing tool on said truing tool slide, a piston and cylinder to traverse said truing tool slide longitudinally, a truing tool feeding mechanism including a fluid pressure actuated pawl and ratchet mechanism actuated by and in timed relation with the traversing movement of said truing tool to feed said tool either at a fine or at a coarse rate at each end of the traversing movement of the truing tool slide, and an independent fluid pressure actuated pawl and ratchet mechanism actuated wheel feed compensator actuated in timed relation with the longitudinal traversing movement of the truing tool slide automatically to impart a rotary motion to the feed screw either at a fine or at a coarse rate during each truing cycle so as to compensate for reduction in diameter of the grinding wheel.

3. In a grinding machine, as claimed in claim 2 in combination with the parts and features therein specified of means including a rotatable nut and a feed screw to feed said truing tool, means including a ratchet wheel to impart a rotary motion to said nut, a pair of independent fluid pressure actuated pawls to actuate said ratchet wheel at the start of the traversing movement of the truing tool slide in either direction to impart a feeding movement to said truing tool, and means independently to vary the extent of feed at each end of the traversing movement of the truing tool.

4. In a grinding machine, according to claim 2, in combination with the parts and features therein specified in which truing tool feeding mechanism includes a rotatable nut and a feed screw, means including a ratchet wheel operatively connected to impart a rotary motion to said nut to feed the truing tool during an intermittent truing cycle, means including an independent ratchet wheel operatively connected to impart a relatively fine rotary motion to said nut at each end of the traversing movement of the truing tool slide during a continuous truing cycle, a pair of independent piston and cylinder actuated pawls to impart a rotary motion to either of the ratchet wheels at each end of the traversing movement of the truing tool slide, and a clutch mechanism to render only one of the ratchet wheels operative at a given time.

5. In a grinding machine as claimed in claim 2, in

combination with the parts and features therein specified in which said wheel feed compensator includes a pawl and ratchet actuated slow speed gear mechanism operatively connected to impart a fine rotary motion to said feed screw during a continuous truing cycle, an independent pawl and ratchet actuated faster speed gear mechanism operatively connected to impart a coarser rotary motion to said feed screw during an intermittent truing cycle, an independent piston and cylinder to actuate each of said pawl and ratchet mechanisms, an independent adjustable stop to limit the movement of said pistons to determine the extent of feed compensation for each actuation, and an independent control valve to render either of said pistons inoperative.

6. In a grinding machine having a grinding wheel truing apparatus including a longitudinally traversable truing tool slide, a transversely movable truing tool thereon, a nut and screw feeding mechanism to feed said tool relative to said slide, means actuated by and in timed relation with the longitudinal movement of the truing tool to actuate the nut and screw mechanism in one direction so as to unwind the feed mechanism, means to thereafter impart a predetermined incremental feeding movement to said feed mechanism and thereafter to actuate said nut and screw mechanism in the opposite direction so as to wind said feed mechanism to position the truing tool for a traversing movement across the operative face of the grinding wheel.

7. In a grinding machine having a grinding wheel truing apparatus including a longitudinally traversable truing tool slide, a transversely movable truing tool thereon, means including a rotatable nut and screw to feed said tool transversely, means actuated by and in

timed relation with the longitudinal movement of the truing tool to actuate said feed nut in one direction so as to unwind said feed nut, means to thereafter impart a predetermined incremental rotary feeding movement to said feed nut and means thereafter to actuate said feed nut in the other direction so as to impart a rotary wind movement of said feed nut to position the truing tool for a traversing movement across the operative face of the grinding wheel.

- 5 8. In a grinding machine having a grinding wheel truing apparatus including a longitudinally traversable truing tool slide, a transversely movable truing tool on said slide, means to traverse said slide longitudinally to traverse the truing tool across the operative face of a grinding wheel, a nut and screw feed mechanism to feed said truing tool transversely, means including adjustable dogs actuated by and in timed relation with the longitudinal movement of the truing tool slide to actuate said feed nut in one direction so as to unwind the feed nut, means to thereafter impart a predetermined incremental rotary feeding movement to said feed nut, and yieldable means thereafter to actuate said feed nut in the opposite direction so as to impart a rotary wind to said feed nut to position the truing tool for a traversing movement across the operative face of the grinding wheel.
